UNITED STATES PATENT OFFICE.

HJALMAR JOHAN RANDERZ, OF BACKEBO NACKA, SWEDEN, ASSIGNOR TO AKTIE-BOLAGET ATLAS DIESEL, OF STOCKHOLM, SWEDEN, A CORPORATION OF SWEDEN.

INTERNAL-COMBUSTION ENGINE.

Application filed February 6, 1923. Serial No. 617,340.

To all whom it may concern:

Be it known that I, HJALMAR JOHAN RANDERZ, a subject of the King of Sweden, and resident of Backebo, Nacka, in the 5 Kingdom of Sweden, have invented certain new and useful Improvements in Internal-Combustion Engines, of which the following is a specification.

This invention relates to an arrangement 10 in internal, combustion engines, by means of which the air in the combustion chamber of the working cylinder at the end of the compression stroke of the piston is caused to whirl and thereby is intimately mingled 15 with the injected fuel. For gaining the said object the provision of a groove or cavity provided in the inner end of the piston and extending round the same and co-operating with a torus provided in the cylinder 20 at its bottom, is combined with a cylinder bottom which is calotte shaped in such manner, that the air, which at the end of the compression stroke is forced from the chamber, enclosed by the bottom wall of the 25 said groove and the side of the torus, and into the combustion chamber of the engine, will move first toward the fuel inlet, centrally located in the cylinder bottom, and then downwards in the same direction as the 30 injected, atomized fuel, the air and the fuel finally whirling round in the combustion chamber.

The accompanying drawing shows as an example and in a vertical section a two 35 stroke cycle engine, to which the invention is applied. The drawing shows in dotted lines the piston in its upper position.

2 is a recess with concave bottom surface and provided in the top end of the piston 1. 40 The said recess extends round the piston. 4 is a torus or shoulder provided at closed end or head of the working cylinder 3 and extending round the inner side of the cylinder, which torus co-operates with the said 45 groove for the purpose stated below. During the operation of the engine the air compressed in the crank chamber 5 passes through the channel 6 and opening 7 into the cylinder, in known manner, and ejects 50 the combustion gases through the outlet 8. As the piston approaches its upper position, shown by dotted lines, the air which is con-

tained in the chamber enclosed by the bottom of the recess 2 and the side of the torus 4, is forced in an oblique direction 55 into the combustion chamber, the walls of which latter are formed by the portion of the piston lying inwardly of the torus 2 and the contiguous portion of the cylinder head. In the drawing, the central portion 60 of the piston is cup-shaped while the cylinder head is calotte shaped, the cross contour of the same being curved shaped and extending from the torus 4 to the fuel inlet or sprayer 9, the radius of the calotte 65 shaped surface in relation to the center line of the cylinder decreasing from the torus. The said air forced into the combustion chamber passes along the calotte shaped side of the cylinder head toward the sprayer 70 9 and then downwards together with the introduced atomized fuel forming forcible whirls resulting in an intimate mixture of fuel and air. Owing to the fact that the air moves downwards from the sprayer 9, thus 75 in the same direction as the fuel, the air has no tendency of counteracting the entrance and spraying of the fuel.

I claim:

In an internal combustion engine the combination with a cylinder having inside a shoulder-shaped part and a piston reciprocally mounted in said cylinder and having a recess in the working face thereof, co-operative with the same shoulder-shaped part, 80 as the piston approaches the limit of its compression stroke, said piston having the portion thereof lying inwardly of the recess cup-shaped, of a cylinder head, having the portion thereof, lying inwardly of the shoulder-shaped part, calotte-shaped with curve-shaped cross section, which right from the said shoulder approaches the longitudinal centre line of the cylinder, and a fuel inlet provided at the centre of the 90 95 calotte-shaped surface.

In testimony whereof, I have signed my name to this specification in the presence of two subscribing witnesses.

HJALMAR JOHAN RANDERZ.
